(57) **CLAIM**

The ornamental design for a knee brace, as shown and described.

DESCRIPTION

FIG. 1 is a front and top perspective view of a knee brace, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is another perspective view thereof;

FIG. 9 is another perspective view of the knee brace shown in an alternate configuration; and,

FIG. 10 is another perspective view of the knee brace shown in an environment of use.

The broken lines showing of a leg in FIG. 10 depict environmental structure that form no part of the claimed design.
